(73) Assignee: **Becton, Dickinson and Company**,
Franklin Lakes, NJ (US)

U.S. Appl. No. 29/664,950, filed Sep. 28, 2018, titled "Sample Container Rack".

(**) Term: **15 Years**

(Continued)

(21) Appl. No.: **29/664,939**

Primary Examiner — Susan Bennett Hattan

(22) Filed: **Sep. 28, 2018**

Assistant Examiner — Rebecca Tsehay

(74) Attorney, Agent, or Firm — Lerner, David,
Littenberg, Krumholz & Mentlik, LLP**Related U.S. Application Data**(62) Division of application No. 29/554,962, filed on Feb.
17, 2016, now Pat. No. Des. 832,454.**DESCRIPTION**(51) **LOC (12) Cl.** ..... **24-02**The present application is also related to U.S. Design patent
application Ser. No. 29/554,966, also entitled Sample Container
Rack and filed on Feb. 17, 2016, as well as U.S.
Design patent application Ser. No. 29/554,968, also entitled
Sample Container Rack and filed on Feb. 17, 2016, the
disclosures all of which are incorporated herein by reference.(52) **U.S. Cl.**USPC ..... **D24/227**(58) **Field of Classification Search**USPC D24/224, 227, 225, 226, 228, 229,

CPC B01L 9/06; B01L 9/065; B01L 3/00; B01L
3/14; B01L 3/50

See application file for complete search history.

FIG. 1 is a front perspective view of a sample container rack
according to our design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

(56) **References Cited**The broken lines illustrate unclaimed environmental structure
and form no part of the claimed design. The dot-dash
broken lines represent unclaimed boundaries and form no
part of the claimed design.**U.S. PATENT DOCUMENTS**D245,118 S 7/1977 Heaton
